UNITED STATES PATENT OFFICE.

MALCOLM E. GRAY, OF ROCHESTER, NEW YORK, ASSIGNOR TO ROCHESTER CAN COMPANY, OF ROCHESTER, NEW YORK, A CORPORATION OF NEW YORK.

DESIGN FOR A PAIL.

Application filed April 13, 1922. Serial No. 1,719. Term of patent 14 years.

To all whom it may concern:

Be it known that I, MALCOLM E. GRAY, a citizen of the United States, residing at Rochester, in the county of Monroe and State of New York, have invented a new, original, and ornamental Design for Pails, of which the following is a specification, reference being had to the accompanying drawings, forming part thereof.

The figure is a perspective view of a pail, showing my new design.

I claim:

The ornamental design for a pail, as shown.

MALCOLM E. GRAY.
